US0D1092780S

(12) **United States Design Patent** (10) **Patent No.:** **US D1,092,780 S**
(45) **Date of Patent:** **** Sep. 9, 2025**

(54) **MEDICAL DRAPE**

(71) Applicant: **Medline Industries, LP**, Northfield, IL (US)

(72) Inventors: **Heidi Frances Hendrix**, Atlanta, GA (US); **David Richard Rawlings**, Cumming, GA (US); **Michelle Wilson**, Caledonia, MS (US)

(73) Assignee: **Medline Industries, LP**, Northfield, IL (US)

(**) Term: **15 Years**

(21) Appl. No.: **29/835,250**

(22) Filed: **Apr. 18, 2022**

Related U.S. Application Data

(62) Division of application No. 29/711,150, filed on Oct. 29, 2019, now Pat. No. Des. 953,572, which is a division of application No. 29/619,202, filed on Sep. 27, 2017, now Pat. No. Des. 869,683.

(57) **CLAIM**

The ornamental design for a medical drape, as shown and described.

DESCRIPTION

FIG. 1 is a perspective view of our new design for a medical drape;

FIG. 2 is a front view thereof;

FIG. 3 is a rear view thereof;

FIG. 4 is a left side view thereof;

FIG. 5 is a right side view thereof; and

FIG. 6 is a top view thereof; and,

FIG. 7 is a bottom view thereof.

The broken lines shown on FIGS. 1-7 illustrate portions of the medical drape that form no part of the claimed design.

1 Claim, 5 Drawing Sheets
